RETROVERTED PASSAGE TYPE MUFFLER WITH EXPANSION CHAMBERS

Filed June 14, 1948

UNITED STATES PATENT OFFICE

2,618,354

RETROVERTED PASSAGE TYPE MUFFLER
WITH EXPANSION CHAMBERS

Gale H. Hedrick, Chicago, Ill., assignor to Maremont Automotive Products, Inc., Chicago, Ill., a corporation of Illinois

Application June 14, 1948, Serial No. 32,957

1 Claim. (Cl. 181—54)

1

This invention relates to mufflers for internal combustion engines.

The primary object of the invention is to provide a muffler of the "three-pass" type wherein means such as a bleeding or cushion chamber is provided to dissipate the kinetic energy and absorb the pressure at one or both ends of the muffler.

Another object of the invention is to provide a three-pass muffler which produces the desired silencing without the use of resonating or tuning chambers.

A further object of the invention is to provide a muffler wherein the sound waves generated by the gas pulses must travel a circuitous and tortuous path and there is no short cut possible for sound waves from the inlet or return tubes of the muffler.

An additional object of the invention is to provide a three-pass muffler which will be self-cleaning.

Referring to the drawings:

Figure 1 is a longitudinal sectional view of my improved muffler;

Figure 2 is an enlarged section on the line 2—2 at the inlet side of the muffler;

Figure 3 is an enlarged section on the line 3—3 at the outlet side of the muffler; and

Figure 4 is a detail view of one of the perforate tubes showing the longitudinally extending circumferentially spaced series of perforations each facing toward an opposite diametrically unperforated portion of the tube.

The muffler comprises a closed casing 10 having end walls or heads 11 and 12. The inlet tube is indicated at 13 and is supported in the end wall 11 and the spaced partitions 14, 15 and 16 within the casing. It will be noted that this tube is spaced from the wall of the casing 10, and its perforations are preferably formed as shown in Figure 4, namely, in longitudinally extending circumferentially spaced series 17, 18 and 19 opening towards diametrically opposite unperforated portions of the tube.

The gas entering the inlet tube 13 has a portion diverted through the aforesaid perforations into the closed intermediate chamber defined by partitions 15 and 16, and another portion introduced to the transverse passageway 20 at the outlet side of the muffler. The gas entering this passageway 20 from the inlet tube 13 is further divided and a portion enters the large opening 21 in a perforated partition 22. The partition 22 defines with the end wall 12 a pressure-relieving and energy-dissipating chamber 23 and it will be

2

noted that the portion of the gas stream which enters such chamber through opening 21 is returned to the passageway 20 through the perforations 24 in the partition 22. The gas which was discharged from the tube 13 to the passageway 20 is thus divided into two portions, both of which must enter the perforated return tube 25 which communicates with the passageway 20, all as indicated by the arrows.

10 In the return travel, as in the case of tube 13, a portion of the gas will pass from the perforations in the tube 25 which are similar to the perforations 17, 18 and 19, into the intermediate closed chamber between the partitions 15 and 16 to thereby further dissipate the energy and pressure.

15 At the discharge end of the return tube 25, namely, at the inlet side of the muffler, there is provided a similar passageway 20, as on the outlet side, and a similar pressure relieving chamber 23, as on the outlet side. Hence, the gas discharged from the return tube 25 is divided, a part passing directly from the passageway 20 to the unperforated outlet tube 26 and another part passing through the large opening 21' to the pressure-relieving and energy-dissipating chamber 23 and back to the passageway 20 through the perforations 24'.

20 The return tube 25, as illustrated, is supported by the unperforated partitions 15 and 16 while the unperforated outlet tube 26, which is also spaced from the wall of the casing, as shown, is supported in the partitions 15, 16, 22 and the end wall 12.

25 While I have shown the cushioning or bleeding chambers provided at both the inlet and outlet sides of the muffler, such energy and pressure dissipating means may be employed at one or the other sides only.

30 It will be noted that the openings 21 and 21' of the chambers 23 are arranged in alignment respectively with the inlet tube 13 and the return tube 25. This is a preferable construction. Also, it will be observed that the perforations 24 and 24' are disposed throughout the area of the wall 14 and the wall 22. Preferably, the passageways 20 and the chambers 23 comprehend the entire area of the casing, as shown.

35 It will be observed that the present invention departs from the usual "three-pass muffler" in the provision of the energy-dissipating and pressure-relieving chambers 23 which, being open to the transverse passageways 20 throughout their areas, as illustrated in Figures 2 and 3, permit the gases to expand therein and cooperate

with the perforated tubes 13 and 25 to additionally dissipate energy and reduce the pressure of the gas pulses.

By reason of this construction there is no need to provide resonating chambers or tuning chambers. Moreover, there is no short-cut for the gases from the inlet tube 13 or the return tubes 25 and 26. The construction shown and described also provides a muffler which has a high self-cleaning efficiency.

I claim:

A muffler comprising a casing with front and rear walls, a pair of spaced transverse partitions disposed within said casing adjacent and spaced in parallel relation to each of said walls so as to define an elongated central chamber, a chamber adjacent each end of said central chamber, and a chamber adjacent each of said front and rear walls, an inlet tube extending from the outside through said front wall and the adjacent partitions and through the partition forming the rear end of said central chamber, said inlet tube being imperforate without said central chamber and being perforate within said central chamber, a return tube having its opposite ends extending through the partitions of said central chamber and being perforate throughout, an imper-

forate outlet tube extending from the outside through said rear wall and the adjacent partitions and through the partition forming the front end of said central chamber, the partition most nearly adjacent the rear wall having a plurality of small perforations and a larger opening therein of substantially the same diameter as, and in axial alignment with, the said inlet tube, the partition most nearly adjacent the front wall having a plurality of small perforations and a larger opening therein of substantially the same diameter as, and in axial alignment with, the said return tube.
